Primary Examiner — Zenia Bennett*Assistant Examiner* — Rashida C McCoy(74) *Attorney, Agent, or Firm* — Venable LLP; Steven J. Schwarz(57) **CLAIM**

The ornamental design for pants, as shown and described.

DESCRIPTION

FIG. 1 is a front-right perspective view of an embodiment of pants according to the claimed design;

FIG. 2 is a rear-left perspective view of the pants of FIG. 1; FIG. 3 is a front elevational view of the pants of FIG. 1; FIG. 4 is a rear elevational view of the pants of FIG. 1; FIG. 5 is a right side elevational view of the pants of FIG. 1; and,

FIG. 6 is a left side elevational view of the pants of FIG. 1. The features shown in broken lines, including stitching, represent portions of the pants which form no part of the claimed design.
